UNITED STATES PATENT OFFICE

163,825

AUTOMOBILE LAMP LENS HOUSING

David E. Scott, Detroit, Mich., assignor to Chrysler Corporation, Highland Park, Mich., a corporation of Delaware

Application April 7, 1950, Serial No. 9,034

Term of patent 7 years

(Cl. D48—32)

To all whom it may concern:

Be it known that I, David E. Scott, a citizen of the United States, residing in the city of Detroit, county of Wayne, and State of Michigan, have invented a new, original, and ornamental Design for an Automobile Lamp Lens Housing, of which the following is a specification, reference being had to the accompanying drawing, forming part thereof, in which:

Fig. 1 is a front elevational view of an automobile lamp lens housing, showing my new design;

Fig. 2 is a top plan view thereof;

Fig. 3 is a side elevational view thereof;

Fig. 4 is a bottom plan view thereof;

Fig. 5 is a cross sectional view taken on the line 5—5 of Fig. 2; and

Fig. 6 is a perspective view thereof wherein the

broken lines indicating an automobile are for illustrative purposes only.

The dominant features of my design reside in those portions shown in the drawings in solid lines.

I claim:

The ornamental design for an automobile lamp lens housing, substantially as shown and described.

DAVID E. SCOTT.
